DESIGN FOR A TEXTILE FABRIC

Louis F. Auger, Ridgewood, N. J., assignor to Stunzi Sons Silk Co., Inc., a corporation of New York

Application November 3, 1936, Serial No. 65,672

Term of patent 3½ years

To all whom it may concern:

Be it known that I, Louis F. Auger, a citizen of the United States, residing at Ridgewood, county of Bergen, and State of New Jersey, have invented a new, original, and ornamental Design for a Textile Fabric, of which the following is a specification, reference being had to the accompanying drawing, forming part thereof, wherein—

The figure is a plan view of a textile fabric showing my new design, with a unit of design outlined in dot and dash lines.

I claim:

The ornamental design for a textile fabric substantially as shown and described.

LOUIS F. AUGER.
